UNITED STATES PATENT OFFICE.

SYLVANUS F. BOWSER, OF FORT WAYNE, INDIANA.

PUMP.

1,137,456.

Specification of Letters Patent. Patented Apr. 27, 1915.

Application filed December 30, 1912. Serial No. 737,787.

To all whom it may concern:

Be it known that I, SYLVANUS F. Bowser, a citizen of the United States, residing at Fort Wayne, in the county of Allen and 5 State of Indiana, have invented certain new and useful Improvements in Pumps, of which the following is a specification.

This invention relates to pumps and more particularly to devices of this class in which 10 the fluid to be pumped is acted upon by a piston reciprocable in a cylinder or casing.

One of the principal objects of the invention is to provide means whereby the position of 15 the piston in the cylinder or casing may be observed from the outside of the casing.

A further object of the invention is to provide means whereby fluid may be ejected from the cylinder when it leaks past the piston, and separate means to discharge air 20 from beneath the piston.

A further object of the invention is to provide improved means for predetermining the amount of fluid to be pumped by one 25 cycle of operations of the piston, at the same time indicating the position of the piston within the cylinder corresponding to the desired quantity to be pumped.

For the attainment of these ends and the accomplishment of other new and useful objects as will appear, the invention consists 30 in the features of novelty in the construction, combination, and arrangement of the several parts generally shown in the accompanying drawings and described in the specification but more particularly pointed out in the appended claims.

In the drawings Figure 1 is a side elevation of a pump constructed in accordance with the principles of my invention; Fig. 2 40 is a top plan view of a pump; Fig. 3 is a sectional view taken on the line 3—3 of Fig. 2; Fig. 4 is a sectional view taken on the line 4—4 of Fig. 3; and Fig. 5 is a detail view of one of the pointers and stops.

In a certain class of pumps it is desirable 45 to see whether or not the full quantity desired is being pumped at each stroke. This is particularly true of the class of pumps known as "measuring pumps" in which the 50 stroke of the piston is varied in length to correspond with the quantity of liquid desired at each stroke. It is obvious that this principle may be applied either to a force pump or to a lift pump. The present ex-

emplification of the invention illustrates its 55 application to a pump of the former class. Some of the features of the present type of pump are shown and claimed in my copending application Serial No. 733,997, filed November 29, 1912.

Referring now more particularly to the drawings, a pump casing 10 of any desirable size or shape is provided with a base member 11 and a cap member 12. Reciprocable in the casing is a piston comprising 60 members 13 which are threaded upon the end of a hollow piston rod 14 and are adapted to retain packing material 15 in position between them and against the inner wall of the casing. Also mounted upon the piston rod 65 14, preferably on the lower end thereof, is a plate 16 which may be secured in position in any desired or suitable manner, as for example, by means of a nut 17 threaded upon the rod. The casing 10 is provided with a 70 number of openings 18 through the wall thereof and preferably in longitudinal alignment. These openings are provided with plates or windows 19 of transparent material which are held in place in any suitable 75 manner, as for example, by means of the frames 20 which are secured to the outside of the cylinder casing. It is obvious, of course, that these openings in the side of the casing should be made fluid tight by the 80 window, at the same time providing means for affording a view of the interior of the cylinder casing. The plate 16 at the bottom of the piston is composed of some suitable material which may be readily visible 85 through the windows in the side of the casing so that the position of the piston may be determined when it is opposite any one of the windows.

The base member 11 is preferably formed 90 with port openings 21 and 22 having the valve seats 23 and 24 respectively. Suitably mounted for free movement with respect to these seats are the valves 25 and 26, preferably arranged so that one valve will be 95 opened and the other closed by one action of the piston in the cylinder 10 and the reverse operation occurring when the piston is moved in the opposite direction. One of the port openings, as 21 is preferably disposed 100 below the cylinder and in the present exemplification of the invention the base casing 11 is formed with a portion extending lat-

erally with respect to the cylinder 10 so that a portion thereof, as 27 forms an extension for the other port 22. Extending from this portion 27 and secured thereto in any suitable manner is a tubular member 28. This tubular member 28 forms the connection for a discharge nozzle 29 (see Figs. 1 and 2).

A packing joint 30 is provided at the upper end of the cylinder preferably in connection with the top or cap member 12 so that the piston rod 14 may pass freely therethrough without loss of compression. Also inserted in the top or cap member 12 is a pipe 31, and extending through this pipe 31 into the cylinder is a tubular member 32. The upper end of the tubular member is threaded into a T 33 which is provided with a tubular member 34 substantially in alignment with the tubular member 32. At the lower end of the member 32 is a shoulder 35 and extending through the tubular members 32 and 34 and through the T 33 is a rod 36. This rod is formed at the lower end with a beveled enlargement 37 and at the upper end with a plug member 38 which may be secured thereto in any desired or suitable manner and which will slide within the tubular member 34. Surrounding the rod 36 and disposed within the tubular members 32 and 34 is a coil spring 39. The enlargement 37 is substantially larger in size than the inside of the pipe 31 so that when brought in engagement with the lower end of the pipe, it forms a closing valve therefor.

In order to move the tubular member 32 and the rod 36 with the piston rod 14, a tubular member 40 connects the T 33 with the body of a valve 41, which is disposed at the upper and outer end of the hollow piston tube 14.

In order to transmit movement to the piston a rack 43 is provided which is movable through the casing 44. Mounted in this casing and having engagement with the teeth 45 of the rack is a pinion 45 secured to a shaft 46. Also secured to the shaft 46 is a gear 47 and meshing with the gear 47 is a pinion 48 mounted upon a shaft 49. Secured to the shaft 49 is a crank 50 having a handle 51. It is obvious that the rotation of the crank 50 will effect the movement of the rack 43. The rack 43 is secured to the piston rod 14 by an arm 52 so that the movement of the rack is imparted directly to the piston rod. Also extending through the top or cap member 12 of the cylinder is a tubular member 53 which projects slightly below the top of the cap but above the top of the piston so that it is just cleared by the piston at the upper end of its stroke. This tubular member is provided with a check valve 54 and with tubular members 55 for connecting it with the discharge nozzle 29. The function of this tubular member 53 is to furnish a passage for the discharge of fluid which has leaked

past the piston in the cylinder. It may happen that during the movement of the piston in the cylinder a quantity of the liquid pumped will leak past the piston and will collect on the top thereof. A certain amount of liquid is of value in sealing the piston and in preventing leakage of fluid past the piston but if this liquid which is disposed above the piston becomes too great in amount there is danger of damaging the cylinder or in knocking off the cap member 12. Another objection to the presence of liquid above the piston is that the liquid which collects above the piston should in reality be discharged through the nozzle and therefore the amount discharged is less than it should be by the amount of liquid which is disposed above the piston. The present construction provides means for discharging superfluous liquid from above the piston into the same nozzle through which the fluid is regularly discharged.

When the piston rod 14 is moved upward in the cylinder by means of the rack 43 the tubular member 32 and the rod 36 are carried with it in the manner previously described. During the upward movement of the piston there is a free escape for the air above the piston through the pipe 31 and around the outside of the tubular member 32, but when the piston approaches the end of its stroke the enlargement 37 of the rod 36 approaches the opening formed in the end of the pipe 31, and when the piston reaches a certain point near the end of the stroke the opening through the pipe 31 will be closed by the beveled surface of the enlargement 37. This will cause the air to be slightly compressed above the piston and if there is any superfluous liquid above the piston the end of the tubular member 53 will first be sealed and then the compression of the air above the piston will be sufficient to force the superfluous liquid outwardly through this tubular member 53 through the check valve 54 and out of the discharge nozzle 29. From this it is obvious that only the superfluous liquid will be discharged from above the piston for, as previously set forth, it is advantageous to have a slight amount of liquid above the piston. It may also happen that air leaks past the piston or is drawn through the valves, and accumulates below the piston, so that an air pocket be formed. When the piston is raised to any one of the windows, if there should be any space between the under side of the piston and the top surface of the liquid, the air has displaced the liquid and must be removed before correct measurement is possible. In order to accomplish this result the valve 41 is located, as previously stated, at the outer end of the hollow piston tube 14. This valve is preferably of the self-closing type and is provided with an operating lever

or handle 42. To discharge the air, the lever 42 is operated to open the valve 41, the piston is then moved downwardly causing the air from beneath the piston to pass up through the tube 14, and through valve 41 to the atmosphere. Then the liquid will fill the entire space below the piston and the pump will deliver an exact predetermined quantity of liquid.

In order to pump a predetermined quantity at each stroke of the piston the rack 43 is commonly provided with a projecting member 56 preferably disposed at the bottom thereof, and a series of stops are provided to limit the travel of the rack and consequently of the piston. In the present exemplification of the invention a threaded rod 57 is provided which extends between the base member 11 and the cap member 12. Adjustably threaded upon this rod 57 are a series of stops. In the present invention these stops comprise a body portion 58 (see Fig. 5) freely movable upon the bar 57, with an extending finger or pointer 59. The central portion of the member is formed with a recess to receive a threaded member 60 having notched edges and adjustable upon the threaded bar 57. A pin 61 is provided which may be inserted through corresponding openings in the member 58 so that it engages one of the notches of the threaded member 60 to hold the latter in any desired fixed position. It will be obvious, of course, that by rotating the threaded member 60 the position of the member 58 may be changed upon the bar 57. Mounted upon a pivot pin 62 and with its pivoted portion extending into the recessed portion of the member 58 is a detent 63 having a projection 64 to engage the member 58 and prevent its rotation beyond a predetermined point, with a straight portion 65 which extends into the path of movement of the projection 56 of the rack 43, and with an extending finger 66, by means of which the detent may be moved into and out of engaging position with the said projection 56. The bar 57 is located in close proximity to the casing of the cylinder as shown more clearly in Fig. 4 so that the extending pointer or finger 59 of the stop member 58 will extend over the frames 20 which hold the transparent members 19 in position. These fingers are adjusted to indicate the correct position of the plate 16 at the bottom of the piston to pump a certain or predetermined amount. This plate 16, as previously explained, is of some material which may be readily visible through the transparent members or windows 19 so that when the piston is raised to pump a predetermined amount the plate 16 shall be in the position indicated by one of the fingers 59 corresponding to this amount. With this construction it is possible to determine whether or not the pump is being operated.

in the proper manner to discharge the full amount. Of course the stop members may be adjusted in position and if desired may be sealed in any desired position by sealing the pin 61 in place.

The operation of the pump need not be explained in detail. In the present exemplification of the invention the fluid to be pumped is drawn through the port 21 by an upward movement of the piston into the cylinder during which action the valve 26 is closed. The downward movement of the piston closes the valve 25 and opens the valve 26, whereupon the fluid is discharged through the tubular member 28 and out of the nozzle 29.

It is obvious, of course, that the cylinder 10 may be constructed entirely of some transparent material such, for example, as glass and it is also evident that liquid may be discharged from beneath the piston through the hollow tube 14, the valve 41, and from the upper side of the piston through pipe 31.

While I have thus described the preferred embodiment of my invention it is obvious that others skilled in the arts to which this relates may make various changes in the construction, combination and arrangement of the several parts without departing from the spirit and scope of my invention.

What I claim is:

1. In a pump, the combination with a cylinder having transparent portions in the walls thereof, of a piston movable in the cylinder, and a plate affixed to the lower side of the piston in direct contact with the liquid and distinguishable through the transparent portion both from the piston and from the liquid pumped.

2. In a pump, the combination with a cylinder having windows therein, of a piston movable in said cylinder and visible through said windows, and an adjustable pointer to indicate the position of the piston to pump a predetermined amount.

3. In a pump, the combination with a cylinder having transparent windows therein, of a piston movable in said cylinder having means distinguishable from the piston and from a liquid in the cylinder and visible through said windows, and adjustable pointers disposed without the cylinder to indicate the positions of the plate within the cylinder at which predetermined amounts will be pumped.

4. In a pump, the combination with a pump casing provided with transparent windows, of a piston movable therein, a plate removably secured to the piston distinguishable therefrom and from a liquid in the cylinder and visible through the windows, and a stop device movable into a position to limit the movement of the piston in one direction, the said plate indicating the position.

tion of the piston through the windows for each stop position.

5. In a pump, the combination with a cylinder provided with transparent windows, of a piston reciprocable therein, a plate secured to said piston and visible through the windows, means to move the piston in the cylinder, and a detent for said means having a finger to indicate the position in which the plate should be for the piston to pump a predetermined amount.

6. In a pump, the combination with a casing provided with transparent windows, of a piston movable therein, a plate secured to said piston and visible through said openings, a rack movable with said piston, and one or more detent devices adjustable to engage the rack at predetermined points, whereupon the pump will discharge a predetermined amount, said detents being each provided with a finger to indicate the position of the plate at which the pump will discharge the predetermined amount.

7. In a pump, the combination with a casing formed with transparent windows, of a piston reciprocable therein having a member visible through said windows and distinguishable from a liquid in the cylinder, valves at one end of said casing, means to limit the movement of the piston in one direction at any predetermined point, the said member which is secured to the piston indicating the position of the piston to pump a predetermined amount, and means at the end of the casing opposite the valve to discharge surplus liquid under pressure from the said end which leaks past the piston.

8. A pump having a reciprocable piston and separate fluid admission and fluid discharge connections, and means operated by the piston in its movement to discharge into the fluid discharge connection any liquid which leaks past the piston.

9. In a pump, the combination with a cylinder, of a piston reciprocable therein, a piston rod extending through one end of the cylinder, valves disposed at the other end of the cylinder, and means in connection with the piston rod to form a restricted passage for discharging under pressure the liquid which leaks past the piston to the end of the cylinder opposite the valves.

10. In a pump, the combination with a cylinder casing, of a piston reciprocable therein, a discharge pipe for the cylinder, and means in connection with the piston for positively discharging liquid exceeding a predetermined amount which leaks past the piston into the said discharge pipe.

11. In a pump, the combination with a casing, of a piston movable therein, pump valves at one end of casing, and means at the other end of the casing for discharging a surplus of liquid which leaks past the piston, said means comprising a port opening

in the end of the casing, a discharge pipe extending below the said port opening, and means to close the port opening when the piston approaches the end of its stroke at this end whereby the liquid first seals the end of the said discharge pipe, and is forced outwardly by the compression due to the continued movement of the piston in the same direction.

12. In a pump, the combination with a vertically disposed cylinder, a piston movable therein, a valve disposed at the lower end of the cylinder, a discharge tube connected with one of said valves, a cap member at the other end of the cylinder having an opening therein, a piston rod movable through said cap member, a tubular member extending through said cap member and forming a fluid tight joint therewith, one end of said tube extending below the cap member and the other end of the tube being connected to the discharge pipe, a check valve disposed in said last named tube, a tubular member extending through the opening in said cap and secured to the piston rod for movement therewith, said tubular member being freely movable through said opening, a rod having a beveled enlargement at its inner end adapted to close the said opening in the cap when the piston is raised, and a spring surrounding said rod in the tubular member adapted to press the beveled enlargement of the rod resiliently against the said opening.

13. The combination in a pump, of a cylinder and pump discharge means, a piston movable in the cylinder, a hollow piston rod, and means other than the pump discharge means to liberate air from beneath the piston through the piston rod.

14. In a pump, the combination with a cylinder and pump discharge means, of a piston movable in the cylinder, a hollow piston rod extending through the piston and through one end of the cylinder, and means other than the normal pumping discharge means in connection with the said rod whereby air may be discharged from between the pump piston and the liquid below it through the hollow piston rod.

15. In a pump, the combination with a cylinder and pump discharge means, of a piston movable in the cylinder, a hollow piston rod extending through the piston and out of one end of the cylinder, a valve at the outer end of the piston rod operative to release air from beneath the piston when it is moved in the cylinder.

16. In a pump, the combination with an upright cylinder and pump discharge means, of a piston movable in the cylinder, a hollow piston rod extending through the piston and out of the top of the cylinder, a valve at the outer end of the piston rod operative to discharge air from beneath the piston through

the piston rod when the piston is moved downwardly in the cylinder.

17. In a pump, the combination with a pump cylinder having windows in the side thereof, of a piston movable therein and visible through the windows, a hollow piston rod extending through the piston and out of one end of the cylinder, and a valve to discharge air from beneath the piston, the presence of air below the piston being evident from an inspection through the said windows.

18. In a pump, the combination with an apertured pump cylinder, windows in said apertures, a piston movable in said cylinder, a plate carried by said piston and visible through said openings, a hollow piston rod extending through the piston and through one end of the cylinder, means to discharge air from the cylinder through the hollow piston rod, the presence of air in the cylinder being evident through the windows when there is a space between the piston and the top of the liquid.

19. In a pump, the combination with a cylinder having transparent windows therein, of a piston movable in the cylinder, a hollow piston rod extending through the piston and one end of the cylinder, means to reciprocate the piston in the cylinder and a valve to liberate air from beneath the piston when the piston is moved downwardly in the cylinder by said means.

20. In a pump, the combination with a pump cylinder having transparent windows therein, of a piston movable in said cylinder, a hollow piston rod extending through the piston and the end of the cylinder, means to move the piston, a combined pointer and stop movable in position to engage the said

means whereby the pointer will indicate the height to which the liquid should rise in the cylinder to discharge a predetermined amount of liquid, the presence of air in the cylinder being shown by a space between the lower side of the piston and the upper level of the liquid and being visible through the windows, and means to discharge the air from the cylinder through the hollow rod when the piston is moved downwardly in the cylinder.

21. The combination in a pump, of a cylinder, a piston movable therein, a hollow piston rod extending through the piston and through the upper end of the cylinder and means to discharge liquid from beneath the piston through the hollow tube out of the cylinder and return it to the cylinder on the other side of the piston.

22. In a pump, the combination with a cylinder, of a piston movable therein, a hollow piston rod extending through the piston and out of the upper end of the cylinder, a tubular connection extending through the upper end of the cylinder to the interior of the cylinder and means to discharge air and liquid from below the piston rod through the tubular connection, the liquid being directed through said tubular connection to the upper side of the piston in the cylinder, and the air being liberated through said tubular connection.

In testimony whereof I have signed my name to this specification, in the presence of two subscribing witnesses, on this 13th day of December, A. D. 1912.

SYLVANUS F. BOWSER.
